Term of patent 14 years

U.S. Cl. D77—1
Int. Cl. D15—01

FIGURE 1 is a perspective view of a portable internal combustion engine embodying our new design;

FIGURE 2 is a perspective view taken from the opposite side thereof;

FIGURE 3 is a side elevational view thereof; and
FIGURE 4 is a top plan view thereof.

The dominant features of our design reside in those portions thereof shown in solid lines.

It is to be understood that the perforations in the circular coverlike wall are distributed throughout the area thereof.

We claim:

The ornamental design for a portable internal combustion engine, as shown and described.
